UNITED STATES PATENT OFFICE.

ISRAEL L. LANDIS, OF LANCASTER, PENNSYLVANIA.

METALLIC CURBING.

SPECIFICATION forming part of Letters Patent No. 456,995, dated August 4, 1891.

Application filed September 27, 1890. Serial No. 366,415. (No model.)

To all whom it may concern:

Be it known that I, ISRAEL L. LANDIS, a citizen of the United States, residing at Lancaster, in the county of Lancaster and State 5 of Pennsylvania, have invented certain new and useful Improvements in Metallic Curb-
ing, of which the following is a specification, reference being had therein to the accom-
panying drawings.

- 10 Referring to the annexed drawings, Figure 1 represents a transverse sectional view of two curbs and the adjacent sidewalks and road-
bed, showing my improvements; Fig. 2, a simi-
lar view, enlarged, showing one of the anchors;
15 and Fig. 3, a similar view showing one of the
anchors provided with a box or loop for the
reception of anchoring-stones.

The invention is designed to produce an im-
proved metallic curbing that will be durable
20 and cheap and firmly established in the earth,
so that it will not tilt or become displaced;
and it consists in certain novel features of
construction, that will fully hereinafter ap-
pear, and be particularly pointed out in the
25 claim appended.

In the drawings annexed, *a* designates the
sheet-metal curbing, which is made in suit-
able lengths and secured together, the upper
edge *a'* of the curbing being turned inward
30 to meet the adjacent sidewalk and its lower
edge being extended into the earth a suitable
distance below the level of the road-bed. Me-
tallic frames or loops *c* are riveted under the
sidewalks to the curbing at suitable intervals,
35 these loops being filled with rocks or stones
to assist in anchoring and steadyng the cur-
bing and prevent tilting thereof. Rods or bars
b, connected together adjustably at their in-
ner overlapping ends by means of a pin *b''*
40 or other device, are extended across the road-
bed or intervening walk, as shown in Fig. 1,

under the stones or blocks thereof, and pro-
vided with upturned ends or arms *b'*, which
are riveted or bolted to the rear side of the
curbing. These rods are placed at suitable 45
intervals along the curbing and serve to brace
and hold the same firmly in position. Being
adjustably connected together, they may be
readily adjusted when placed in position to
the width of walk or road-bed desired. 50

At suitable intervals along the curbing I
attach anchors *d*, as shown in Fig. 2, which
are provided with lateral feet or arms *d' d'*,
projecting in opposite directions. Suitable
stones are placed under these anchors and 55
upon their feet or arms, as shown, to assist in
establishing them. The anchors are formed
with sockets at their upper ends for the re-
ception of the lower edge of the curbing, which
is bolted or riveted thereto. 60

In Fig. 3 the anchor is shown provided with
a box or loop for the reception of anchoring-
stones. 65

Having thus fully described my invention,
what I claim is—

The combination of two metallic curbings
having their lower edges inserted in the earth,
anchors *d*, connected to the lower edges of
the curbings and extending into the earth,
rigid loops *c*, secured to the back of the curb-
ings and extending back into the earth and 70
adapted to be filled with stones, and a pair
of inwardly-extending rods secured to the op-
posite curbings and adjustably secured to-
gether at their inner overlapped ends, as and 75
for the purposes set forth.

In testimony whereof I affix my signature in
presence of two witnesses.

ISRAEL L. LANDIS.
